CRUTCH HEAD CAP

Filed Jan. 7, 1933

INVENTOR
HORACE M. HIGGINS.

BY
David O. Barnell.

ATTORNEY

UNITED STATES PATENT OFFICE

HORACE M. HIGGINS, OF OMAHA, NEBRASKA

CRUTCH-HEAD CAP

Application filed January 7, 1933. Serial No. 650,676.

My invention relates to crutches, and particularly to means for covering the head or arm-rest of a crutch. Persons who are obliged to use crutches for a considerable time, find that it is undesirable to support the weight of their bodies upon the head or portion of the crutch which extends beneath the arm-pit, and that the crutch may be used with much greater comfort and facility when the greater part, if not all of the weight of the user is supported through the arms and hands, upon the grip or hand-piece of the crutch. It is found also, by users of crutches for an extensive period, that it is undesirable to provide upon a crutch-head any soft cushion or covering of such thickness as to have a cushioning effect, as the use of a cushion of any appreciable depth causes pressure upon the blood-vessels which traverse the arm-pit, thus restricting the blood circulation through the arm, and causing numbness or other discomfort to the user. When crutches are used with the weight of the body carried either upon the crutch-heads at the arm-pits, or upon the hands at the grips of the crutches, there is caused a relative movement between the crutch-heads and the clothing of the user, beneath the arms, so that the clothing rapidly becomes worn by the rubbing of the crutch-heads thereon. It is the object of my invention to provide means for preventing such wear of the clothing, and to prevent also any pulling upon the clothing, tending to distort or wrinkle the same, by the movements of the crutch-head relative to the body and arm of the user. A further object of my invention is to provide an article for the purposes indicated, which may be produced at a nominal cost, quickly and inexpensively replaced when worn out, readily cleansed when it becomes soiled, and which will not be clumsy or unsightly in appearance.

In the accompanying drawing Fig. 1 is a side view of a crutch provided with a cap or head-cover embodying my invention, and Fig. 2 is a transverse vertical section on the line 2—2 of Fig. 1.

In carrying out my invention, the cap or cover for the crutch-head is made of pliable

material, such as fabric or soft leather, of which the thickness is insufficient to afford any appreciable cushioning effect by being interposed between the crutch-head and the body of the user. The protective cap of pliable material comprises opposite approximately parallel side portions 3 and 4 which are joined together at the ends 5 and 6 and at the top 7, to cover and inclose the top and ends of the upper cross-piece or arm-rest 8 of the crutch. The top portion 7 of the cap is curved concavely from end to end, to fit approximately the concave of the arm-rest 8, the length of the cap is greater than that of the arm-rest so as to normally extend beyond the same at both ends, and the upper corners of the cap are rounded to conformity with the ends of the arm-rest, substantially as shown. The ends 5 and 6 of the cap are oblique and converge toward the lower or open edges of the side portions 3 and 4, so that at said open bottom edge said ends of the cap are normally spaced from the upright side-pieces 9 of the crutch, about the same distance that the upper portions of the ends are spaced from the ends of the arm-rest. To prevent displacement of the cap from the crutch-head, means are provided for connecting the side portions 3 and 4 under the arm-rest 8, between the side-pieces 9 of the crutch, said connecting means comprising, in the structure shown in the drawing, a separable snap-fastener 10 of the ordinary type used on gloves, one of the separable parts of the fastener being affixed to each of said side portions of the cap. The depth or vertical dimension of the cap is such as to allow the same to fit loosely about the arm-rest when the side portions are drawn together beneath the arm-rest to connect the fastener-members to each other.

The oblique convergent formation of the ends of the cap, whereby said ends normally extend in beneath the ends of the arm-rest, serves to prevent the ends of the cap being lifted off the arm-rest accidentally by the user when swinging the crutch-heads in beneath his arms preparatory to use thereof. The cap as a whole is so shaped and proportioned that, when the fastener-members are

disconnected and the cap is moved longitudinally toward one end of the arm-rest, the projecting end of the cap may be lifted off over said end of the arm-rest, and the 5 cap then completely removed by sliding it longitudinally toward the other end of the arm-rest.

In the use of a crutch provided with a cap or cover in accordance with my invention, the cap tends to cling to the clothing of the user, so as not to move relative to the clothing, while the necessary movements of the crutch-head are made within the cap, which thereby receives all of the wear resulting from the movement. The described mode of operation results from the fact that the head or arm-rest of the crutch, being hard and smooth, has a lower coefficient of friction with the material in the cap than the latter 10 has with the clothing of the user, and the cap is made enough longer than the arm-rest to enable the necessary movements of the crutch without causing movements of the cap. The form of the cap, and the means employed for retaining the same upon the crutch-head, prevent accidental loss or displacement of the cap, while permitting free movement of the crutch to the extent necessary in the use thereof, and preventing pulling 15 upon the clothing, or wrinkling or wear of the same. The cap may be readily removed for cleansing or replacement, and the material used in the cap may if desired be of a texture and color such as to harmonize with the clothing of the user.

Now, having described my invention, what I claim and desire to secure by Letters Patent is:

1. A crutch-head cap, comprising a cover 20 of relatively thin pliable material, closed at the top and ends and open at the lower side thereof, and adapted to fit loosely about the arm-rest of a crutch so that the latter is freely movable longitudinally therein, and means for retaining said cover in place upon the crutch-head.
2. A crutch-head cap, comprising a cover 25 of relatively thin, and pliable material, having closed top and ends and substantially parallel side portions, the closed top and ends of said cover conforming generally with the respective contours of the arm-rest of a crutch, the length of the cover being greater than the length of the arm-rest whereby the cover is adapted to fit loosely over the arm-rest and enable relative longitudinal movements of said parts, the lower side of the cover having an opening through which the arm-rest may be inserted for inclosure by the cover, and means for connecting the side portions of the cover beneath the arm-rest.
3. A crutch-head cap, comprising a cover 30 of relatively thin and pliable material having closed top and end portions conforming generally with the respective contours of

the arm-rest of a crutch, the length of the cover being greater than the length of the arm-rest whereby the latter is movable longitudinally within the cover, the ends of the cover converging toward the open lower side 70 thereof whereby to extend normally beneath the ends of the arm-rest, the side portions of the cover being substantially parallel and adapted to fit loosely about the sides of the arm-rest and extending beneath the same, and separable connecting means for securing together the side portions of the cover beneath the arm-rest.
